UNITED STATES PATENT OFFICE.

FREDERICK A. HUBEL AND JESSE M. SMITH, OF DETROIT, MICHIGAN; SAID SMITH ASSIGNOR TO SAID HUBEL.

CAPSULE-MACHINE.

SPECIFICATION forming part of Letters Patent No. 557,073, dated March 24, 1896.

Application filed January 20, 1894. Serial No. 497,551. (No mode!.)

To all whom it may concern:

Be it known that we, FREDERICK A. HUBEL and JESSE M. SMITH, citizens of the United States, residing at Detroit, county of Wayne, 5 State of Michigan, have invented a certain new and useful Improvement in Capsule-Cutting Machines; and we declare the following to be a full, clear, and exact description of the invention, such as will enable others skilled in the art to which it pertains to make and use the same, reference being had to the accompanying drawings, which form a part of this specification.

This invention relates to capsule-cutting machines, and has for its object improvements in that class of machines in which a capsule is trimmed and stripped from the mold upon which it is formed.

The special object of the improvement is 20 to produce a perfectly-symmetrical evenly-trimmed capsule which shall be accurate in size and holding capacity, and which shall have its edges smooth and true without being torn or broken.

Another object of our invention is to produce a machine which shall trim and strip the capsule from the mold at one operation.

In the drawings, Figure 1, Sheet 1, shows a front view of the machine. Fig. 2, Sheet 2, 30 shows a view of the right-hand side of the machine. Fig. 3, Sheet 3, shows a vertical section of the machine at right angles to the main shaft. Fig. 4, Sheet 4, shows a top view of the machine with the spreader-head removed. Fig. 5, Sheet 4, shows a horizontal section at line xx , Fig. 1. Fig. 6, Sheet 3, is an enlarged horizontal section of the cutter and push-arms, showing their relation to each other and to a capsule-mold pin. Fig. 7, Sheet 2, shows 40 a plan view of the clutch mechanism, showing the inclined lugs and actuating-springs.

The object of the invention is to cut off the end of the capsule to the proper length and to push back the refuse so cut off and leave 45 it apart from the capsule.

The capsule is formed by covering the mold-pin of the desired shape with a film of gelatine or other substance. One or more of these mold-pins are secured to a plate, and one or 50 more of these plates are operated upon by the machine. In the drawings, a machine is shown

to operate upon one mold-plate carrying eighteen mold-pins, but the machine may be enlarged to operate on any number of mold-plates, carrying any number of pins desired 55 without departing from the invention.

In this invention the capsules are cut to the proper length by a circular cutter whose cutting-edge rolls on the surface of the mold-pin and is held to its work by a yielding pressure in the manner set forth in the patent of Frederick A. Hubel, dated February 13, 1877, No. 187,279. In the machine of said patent, as used in practice, the cutter, besides being used to cut, was also used to push back the 65 refuse material, resulting in rapid and uneven wear of the cutting-edge. In the present invention the cutter is only used for cutting, and is then held back while the push-lips are let into the cut and push the refuse back. 70

In the drawings, A A are the side pieces of the frame, properly connected together by the top plate B, cross-bar C, and rods D to form the framework.

E is a table secured to a plate F, which is 75 adjustably secured to a plate G. The plate F is connected to the frame by means of vertical adjustable guideways H formed in the frame, which permit a vertical motion of the plate and its table E. (See Fig. 5.) The plate 80 G has formed on it journal-bearings I in which the shaft J revolves. On the shaft J are rollers K, which roll on the cams L secured to the main shaft M, which shaft is journaled in the frame. The vertical motion of the table 85 E is thus controlled by the cam L.

A single cam L and roller K may be used, but I prefer two.

In order to regulate the length of the capsules the table E and its plate F are made 90 vertically adjustable with reference to the plate G. The means shown in the drawings for obtaining this adjustment consist of two screws N N, intermediate between the bearings I I, fixed to the plate G and the plate F. 95

Each screw has fixed to it a pinion O, which engages a gear-wheel P fixed to the shaft Q. The shaft Q is journaled in lugs formed on the plate F, and has fixed to it a handle R, by which it and the gear-wheels and screws N N 100 may be simultaneously turned. The turning of the screws N N by the handle R causes the

table E to move vertically, and when the table is at the desired adjustment it is clamped firmly in place by the following-described means: Two studs S S pass loosely through 5 vertical slots in the plate F and are made fast to the plate G. (See Fig. 5.) A yoke T connects the ends of the studs S S, and the position of the yoke is made adjustable by the nuts U U screwed on the studs. A lever V is journaled 10 on the shaft Q. The hub of the lever V is connected to the yoke T by the toggle-link W. When the lever V is moved so as to straighten the toggle, as shown in Fig. 5, the plate G is drawn tightly against the plate F, and this 15 same movement clamps the shaft Q.

Other means for adjusting and clamping the table E than those described and shown in the drawings may evidently be used without departing from my invention.

20 A mold-plate is shown at A' carrying eighteen capsule-mold pins B'. This mold-plate rests on the top of the table E and is held in position on the two sides and back by strips C' C' fixed to the table. On the front the 25 mold-plate is held and clamped in position by one or more movable dogs D'. This dog passes through a slot in the table, the upper end pressing against the edge of the mold-plate.

The dog is carried on a rod E', on which it 30 can slide. It is forced inward by a spring F', and is held from moving too far by a collar G' on the rod E'. The inner end of the rod E' is pivoted to a block H', which slides in a 35 notch formed in the plate F. The outer end of the rod E' is connected to a crank-shaft I' journaled in lugs fixed to the table. A handle J' (see Figs. 1 and 2) is fixed to crank-shaft I' and serves to turn it. The handle is provided with suitable catch and stops K' K' 40 to hold it in its extreme positions. The circular motion of the outer end of the rod E' and the linear motion of its inner end causes the dog D' to move back and down below the 45 surface of the table when the handle J' is moved down to its lower stop K', thus leaving the table clear for placing the mold-plates and removing them.

The cutters are in the form of round disks a, with sharp edges. (See Figs. 3 to 6.) These 50 cutters are suitably journaled on the ends of arms b, which are secured at their other ends to revolving heads c. Each head c is secured to one end of a hollow shaft d, which is journaled in the top plate B, and the bar e 55 fixed to said top plate. Each shaft d has a pinion f fixed to it and another pinion g loose upon it. The alternate shafts d have the fixed pinion above the loose one, while the other shafts have the fixed pinion below the 60 loose one. All the upper pinions on all the shafts gear into each other and form one set, while all the lower pinions gear into each other and form a second set.

One set of pinions is driven by one of the 65 gears h and the other set is driven by the other gear h. The gears h are preferably double the diameter of the pinions f and g,

so that one-half revolution of h will cause a complete revolution of the pinions.

The gears h are fixed to shafts i, which are 70 journaled in the frame, and are driven by shaft j through miter-gears k k. The shaft j is also journaled in the frame, and has fixed to it a gear-wheel l. The gear l engages a segmental gear m (see Fig. 2) fixed to the 75 main shaft M.

There are two rollers n n, which turn on journals fixed to the gear-wheel l. These rollers roll on the edge of a circular flange o fixed concentric on the shaft M. The rollers n n when in contact with the flange o prevent the shaft j and the cutter-heads c from turning. That part of the flange o opposite to the segmental gear m is cut away, so that when the gear m engages the gear l the latter 85 is turned through a little more than one hundred and eighty degrees, until the gear m is disengaged from gear l, when one of the rollers n comes in contact with the inclined part p of the flange o. The roller n, in moving 90 up on the incline p, turns the shaft j slightly backward and then locks the shaft again, when both rollers are on the cylindrical part of the flange o.

Besides the cutter-arm b, each of the heads 95 c has fixed to it one or more push-arms q. Each push-arm is provided at its free end with a lip r projecting inward toward the mold-pin. (See Figs. 3 to 6.)

All the cutter and push-arms are flattened 100 near where they are connected to the heads c, so as to form springs.

The spring part of the arms are bent to such a form that the free ends of the arms all tend to press inward toward the mold-pin. 105 They are all held out by spreader-rods s s, passing down through the centers of the hollow shafts d d.

Each cutter and push-arm has a cam-shaped 110 projection t on its inner side below the spring, which bears against the spreader-rod and holds the free end of the arm back. The cams t on the cutter-arms are not opposite the cams on the push-arms. The spreader-rods are reduced in diameter, as shown at v. 115

When the spreader-rods are in the position shown in Fig. 3, the cutters and pushers are all held back. If the spreader-rod be pushed down, the cam t on the cutter-arm will enter the reduced part v and let the cutter in 120 against the mold-pin, but still hold the pushers out. If the spreader be pushed still farther down, the cam t of the cutter-arm will ride up on the rod again and move the cutter out, while the cam t on the pusher will 125 enter the reduced part v and let the pushers in against the mold-pin. The return of the spreader to its original position will bring the cutter and push-arms to their original positions. (Shown in Figs. 3 and 6.)

130 Motion is given to the spreader-rods by the means described as follows: All the spreader-rods are connected to a plate a', forming part of the spreader-head b'. This head has con-

nected to it two rods $c' c'$, which are guided for vertical motion by slides $d' d'$ on the frame. Each rod has a roller e' journaled to it, which roller travels on the edge of a cam-
5 disk f , fixed to the main shaft M . The profile of this cam is shown at f , Fig. 2, which also shows the profile of the table-lifting cam L .

Motion is given to the machine through a
10 pulley g' mounted loosely on the main shaft M . The hub of the pulley has formed upon it the teeth h of a clutch. The other half i' of the clutch is connected to rods j' , which slide parallel to the shaft in a hub k' , which is fixed to the shaft. The ends of the rods j' are connected together by a plate l' , and this plate has fixed to it an inclined lug n' . A similar but reversed lug o' is fixed to a collar which encircles the hub k' , and in which the
15 hub freely turns. The collar is formed with an arm m' , which is connected by a rod p' to the end of a lever q' , which latter is fixed to a shaft r' journaled in the frame. Springs $k^2 k^3$ are seated in the hub k' , and arranged
20 to force the half-clutch i into engagement with the half-clutch h' . To the shaft r' is fixed an arm s' , which engages at its free end with a lug t' fixed to one of the cams f' . To the same shaft is fixed an arm v' , connected
25 by a rod w' with the starting-lever x' . A spring z' holds these parts in the position shown in Fig. 2.

The form of driving mechanism, clutch and starting mechanism described and shown in the drawings is well adapted for the work;
30 but any other form which will give the required intermittent motion of the main shaft may be used.

The starting mechanism may be connected
35 to the plate-locking handle J' , so that the motion of locking the mold-plates will start the machine; also the handle J' may be unlocked automatically during the descent of the table
40 E . These are conveniences which add to the rapidity of operation of the machine.

The operation of the machine is described as follows: The machine being at rest, the handle V is moved to unclamp plate F from plate G . The handle R is then moved to raise
45 or lower the table E to an adjustment giving the desired length of capsule. The plates F and G are then clamped by handle V . The mold plate or plates, having the mold-pins covered with gelatine, or other substance of
50 proper consistence, are then placed on the table and moved back against the stop C' . The locking-handle J' is then turned so as to throw the dogs D' up and lock the plates in position. The starting-handle x' is next
55 moved so as to throw the end of arm S' out of engagement with lug t' and at the same time move the arm m' so that the inclined lug o' travels past the lug n' . This motion unlocks the main shaft M and also permits the two
60 halves of the clutch $h' i'$ to be brought into engagement with each other by the springs
65 $k^2 k^3$, so that the motion of the pulley g' is

communicated to the shaft M . The shaft M revolves until the inclined lug n' moves up onto the lug o' and draws the half-clutch i' out of engagement with the half-clutch h' , when the motion of the shaft ceases and is positively stopped by the lug t' coming in contact with the end of arms s' . During the one complete revolution of the main shaft the motion of the other parts succeed each other in the following order: The table is first raised by the cam L till the cut-off line is directly opposite the edge of the cutters and rests in that position. Next the spreader-rods are moved down by cam f' , which lets the cutters in against the mold-pins and then rest. The segmental gear m then engages the gear l , which causes the cutters to turn about and in contact with the mold-pins and cut off the capsule. Near the end of this last movement the spreaders are moved down so as to throw the cutters out and then rest. At about the same time the roller n , traveling on the incline p , turns the cutters back to their original position, where they rest and are locked by the two rollers $n n$, resting on the circular flange o . Next the table is raised by cam L until the cut-off line comes just opposite the lips r of the pushers and then comes to rest. The spreaders are then moved down, letting the lips of the pushers in against the mold-pins and they rest. The table is then raised again and the refuse is pushed back on the mold-pins, as shown in Fig. 3, and it rests. The spreaders are then raised by the cam f' to their original position, (shown in Fig. 3,) thus moving and holding the cutter and push-arms out and they rest. The table is now lowered by the cam L , which is positively stopped in its original position by the lug t' and arm s' . The locking-handle J' is next thrown down, and the mold-plates removed, thus completing the cycle.

What we claim is—

1. In a machine for trimming gelatine capsules, the combination of a table for holding the molds, a cutter adapted to roll in contact with the capsule whereby the lower edge of the capsule is trimmed off, a push-lip, having its edge arranged at right angles to the axis of said capsule and adapted to engage in the cut formed by said cutter at the time that said cutter is disengaged therefrom, and means for adjusting said table, whereby the refuse is pushed back in a line parallel with the axis of said capsule, substantially as described.

2. In a capsule-trimming machine, the combination of a supporting-frame with a table supported in said frame, arms supported at the lower ends of hollow shafts, revolving cutters and push-lips secured at the lower ends of said arms, adjustable rods within said hollow shafts having a reduced part at their lower ends, lugs on said arms adapted to engage the lower ends and reduced parts of said rods, whereby said cutters and push-lips are forced into and out of engagement with said

capsules, and means for revolving said hollow shafts whereby said cutters and push-lips are made to turn around said capsules, substantially as and for the purpose described.

- 5 3. In a capsule-trimming machine, the combination of a supporting-frame, a table adapted to support the plate carrying mold-pins, hollow shafts journaled in the upper end of said supporting-frame, cutters and push-lips
 10 supported from the lower ends of said hollow shafts, means for rotating said hollow shafts whereby said cutters and push-lips are made to turn around said capsules, rods within said hollow shafts having their upper ends engaged
 15 with a yoke, cam-wheels supported on a shaft journaled in said frame and adapted to raise and lower said rods whereby said cutters and push-lips are brought into and out of engagement with said capsules, means for driving
 20 said shaft, and means for stopping said shaft at every complete revolution, substantially as, and for the purpose described.
4. In a capsule-trimming machine, the combination of a supporting-frame, a table adjustably supported in said frame, vertical hollow shafts journaled in the upper end of the frame, spring-arms supported at the lower ends of said hollow shafts, revolving cutters and push-lips secured at the lower ends of
 25 said spring-arms, adjustable rods within said hollow shafts having a reduced part at their lower ends, lugs on said spring-arms adapted to engage the lower ends and reduced parts of said rods whereby said cutters and push-lips are forced out of, or allowed to spring into
 30 engagement with the capsules, and means for revolving said hollow shafts whereby said cutters are made to roll around and trim said

capsules, substantially as and for the purpose described.

5. In a capsule-trimming machine, the combination of a supporting-frame, a table mounted in said frame, adapted to support plates carrying mold-pins, cutters and push-lips adapted to rotate around said mold-pins, means whereby said mold-pins are given an intermittent movement with respect to the cutters and push-lips, and means whereby said cutters and push-lips are swung into and out of engagement with said mold-pins, substantially as and for the purpose described.

6. In a capsule-trimming machine, the combination of a supporting-frame, an auxiliary frame guided in ways formed in said supporting-frame and carrying a table, said table adapted to support a plate having mold-pins mounted thereon, means whereby said plate is firmly secured to said table, a shaft carrying rollers at its outer ends, journaled in said auxiliary frame, a second shaft journaled in said supporting-frame, and carrying cam-wheels adapted to engage with said rollers whereby said auxiliary frame is compelled to rise and lower at every complete revolution of said cam-wheels, a loose driving-pulley mounted on said second shaft, and means for starting and stopping said cam-wheels at every complete revolution, substantially as and for the purpose described.

In testimony whereof we sign this specification in the presence of two witnesses.

FREDERICK A. HUBEL.

JESSE M. SMITH.
